UNITED STATES PATENT OFFICE.

SIGISMUND M. MICHELSON, OF MILWAUKEE, WISCONSIN, ASSIGNOR OF
ONE-HALF TO GEORGE SYLVESTER, OF SAME PLACE.

TRUNK OR FURNITURE CASTER.

SPECIFICATION forming part of Letters Patent No. 349,948, dated September 28, 1886.

Application filed July 20, 1885. Serial No. 172,062. (Model.)

To all whom it may concern:

Be it known that I, SIGISMUND M. MICHELSON, of Milwaukee, in the county of Milwaukee, and in the State of Wisconsin, have 5 invented certain new and useful Improvements in Trunk or Furniture Casters; and I do hereby declare that the following is a full, clear, and exact description thereof.

My invention relates to trunk-casters, and 10 will be fully described hereinafter.

In the drawings, Figure 1 is a section of my improved caster. Figs. 2, 5, 6, and 7 are like sections of modifications of the same. Fig. 3 is a rear edge view of the caster shown in Fig. 15. Fig. 4 is a front edge view of the same 20 caster, the housing being omitted in Figs. 3 and 4, to clearly show the construction and arrangement of the parts which would otherwise be concealed thereby. Fig. 8 is a plan view of 25 the base-plate removed from the rest of the 20 caster. Fig. 9 is a plan view of the base-plate in position on the caster. Figs. 10 and 11 are respectively perspective and plan views of a locking-lug for securing the base-plate and 25 caster together. Figs. 12 to 17 are details of parts hereinafter referred to.

A is the base-plate, which, as shown in Figs. 8 and 9, is formed with a series of key-hole 30 slots, *a*, near its outer edge, and a preferably larger key-hole slot, *a'*, near its center.

B is a wheel-frame, which is shown in plan in Fig. 12, and which is provided with a key-hole slot, *1*, intermediate between the bearings for the large wheel *b* and those for the smaller 35 wheel, *b'*.

b' are grooved wheels, which are let into the upper portion of the wheel-frame, as shown in Fig. 1, and these work up against an annular rib, *c'*.

40 The bottom piece, D, of the caster is slotted, as at *d*, and has cast with it hangers *D'*, to receive the axle of the large wheel *b*, and the axle is held in place in the hangers by projections *B'*, that extend down from the casting B, which latter forms the wheel-frame, an opening, *B'*, being left in the wheel-frame between the projections *B'*, to receive the upper portions of the wheel.

45 F is a center-pin, which holds the bottom piece, D, in place, and F' is a locking-lug for securing the center-pin in place.

When my device is to be put together, the wheel-frame is placed upon the bottom plate, D, after the bolt F has been placed in the slot *d* in said bottom plate, and the axle of wheel *b* 55 has been placed in its bearings in such bottom plate, the base-plate is placed upon the wheel-frame, with the head of bolt F projecting through the larger portion of the key-slot *a'*, formed therein. Said base-plate is then moved 60 to one side until it coincides with the bottom plate and the bolt is caught by the narrow portion of the slot *a'*. The lug F' is then inserted in slot *a'*, to lock the bolt in. The caster thus put together is then slipped into the 65 housing G, the heads of the rivets *g* passing through the larger portions of the key-openings *a*, the base-plate is turned into the position shown in Fig. 9, and the parts thus securely locked together. The locking-lug F', (shown 70 in detail in Figs. 10 and 11) consists of a round depending hub adapted to fit just within the largest or circular part of the key-hole slot *a'* in the plate A, while the lug is prevented from dropping through said slot by 75 means of two little wings or flanges, one on each side of the upper part of said hub, and from the latter part there extends a projection just the width of the long narrow part of the 80 said key-hole slot *a'*, but of less length, and beveled on top toward its end, so that when the bolt F is in place, as just described, the beveled end of the said projection will fit under the upper head of said bolt F, and thus the key-hole slot *a'* will be completely closed 85 up, and the bolt F prevented from moving out of place.

In the modification shown in Fig. 5 the bottom piece, D, has hangers similar to those in Fig. 1, and wheel-frame B is similar in construction to that shown in Fig. 1, except that instead of using the loose pin F, I form the bottom piece with a pin which is somewhat pointed on top, and a cap, *h*, is placed upon it, so that when the plate A is placed upon 95 the annulus or housing G the apex of the cap will extend up through a central opening or into an indentation in the base-plate, which latter is secured upon the housing, as in Fig. 1. In the modification shown in Fig. 6 the 100 wheel-frame is similar to that shown in Fig. 1, and the pin F is locked in a base-plate by a

lug, F'; but the bottom plate is dispensed with, and the large wheel b is hung directly from the wheel-frame. In Fig. 7 only two wheels are used—a small one that is let into the wheel-frame and is flanged to fit on an annular rib, c, and the wheel which is hung directly beneath it to the wheel-frame. The wheel-frame in this instance has a pin cast or otherwise formed with it that extends up through a key-hole opening, and is locked by a lug that differs only slightly from that in Fig. 1, and the head of the bolt is covered by a cap, f. In these last two modifications lateral displacement of the wheel-frame is prevented by the annular ribs c, acting on the flanges of wheels b'.

In the modification shown in Fig. 2 the bottom plate, D, is made in one piece with the housing G, and while the base-plate is secured to the trunk or furniture-leg by any suitable means the parts are locked together by pin F, as in Fig. 1.

In Figs. 14 and 16 I dispense with small wheels entirely, and simply use a frame, B, for centering the bottom plate, this frame having depending lugs B', for holding the axle of the large wheel in place.

In Fig. 17 I show a frame similar to that in Fig. 16, with notches h' on its sides, and this I place in a cup, D G, the annulus G of which is notched, as at h', to receive one end of an axle that is supported at its other end in a similar notch in the frame. These wheels b', Fig. 17, may be either flanged or grooved, as in Figs. 5 and 6.

Having thus described my invention, what I claim as new, and desire to secure by Letters Patent, is—

1. In a trunk or furniture caster, the combination, with a housing, of a wheel-frame, slotted bottom and base plates, and a locking-pin and locking-lug adapted to fit within the central slot in the base-plate, as set forth. 40

2. The base-plate have key-hole slots, as described, in combination with the housing G, having projecting rivets g, slotted wheel-frame 45 and bottom plate, a locking-pin, and locking-lug, as set forth.

3. The combination, in a trunk or furniture caster, of a slotted wheel-frame having projections B' with a bottom plate having hangers 50 D' and a center-pin, slotted base-plate, and locking-lug, as set forth.

4. The combination, in a trunk or furniture caster, of a wheel-frame and slotted base-plate made separate from each other and detachably 55 connected by a pin, F, and locking-lug, as set forth.

In testimony that I claim the foregoing I have hereunto set my hand, at Milwaukee, in the county of Milwaukee and State of Wisconsin, in the presence of two witnesses.

SIGISMUND M. MICHELSON.
